Primary Examiner—C. A. Murphy[57] **CLAIM**

The ornamental design for a contact lens package, as shown and described.

DESCRIPTION

FIG. 1 is a perspective view of a contact lens package showing our new design;

FIG. 2 is a right side elevational view thereof; the left side being a mirror image;

FIG. 3 is a top plan view thereof;

FIG. 4 is a bottom plan view thereof;

FIG. 5 is a rear elevational view thereof; and,

FIG. 6 is a front elevational view thereof.

FIG-1

FIG-2

FIG-3

FIG-4
